UNITED STATES PATENT OFFICE.

HARRY R. MASON, OF CHICAGO, ILLINOIS, ASSIGNOR TO THE WESTING-HOUSE AIR BRAKE COMPANY, OF PITTSBURG, PENNSYLVANIA, A CORPORATION OF PENNSYLVANIA.

FLUID-PRESSURE SIGNAL-VALVE.

SPECIFICATION forming part of Letters Patent No. 693,415, dated February 18, 1902.

Application filed June 12, 1900. Serial No. 20,010. (No model.)

To all whom it may concern:

Be it known that I, HARRY R. MASON, a citizen of the United States, residing at Chicago, county of Cook, State of Illinois, have invented or discovered a certain new and useful Improvement in Fluid-Pressure Signal-Valves, of which improvement the following is a specification.

My invention relates to an improvement in signal-valves employed in fluid-pressure signaling systems to sound the signal when actuated by impulses generated in the signaling-pipe. The signaling system is used more especially upon railway passenger-trains and employs a signaling-pipe extending throughout the train and kept charged with air under pressure from the main reservoir of an air-brake system. The signal is actuated by the opening of a conductor's signaling-valve upon a car of the train to generate a signaling impulse which travels to the signal-valve on the locomotive, the object being to cause each opening of a conductor's signaling-valve to actuate the signal-valve on the locomotive and sound the signal, usually a whistle, once and once only with each operation.

It is a fact well known in the art that the effects of impulses generated at conductors' signaling-valves vary greatly in trains of different lengths, so that the force of an impulse when it reaches the signal-valve may be of greater or less degree, dependent upon the number of cars in the train and the relative position of the conductor's valve that is opened. The variations mentioned are increased by the fluctuations of pressure in the train-pipe following the direct impulse. As a consequence unless means are provided to prevent it the signal-valve will be actuated and the signal sounded more than once under a single direct impulse. In Letters Patent that have been hitherto granted to me, notably No. 534,401, of February 19, 1895, and No. 620,601, of March 7, 1899, I have shown and described signal-valves of what is known as the "non-interference" type constructed to prevent the undue repetition of signals by causing the return of the sig-

nal-valve piston, which shuts off the whistle-valve, to be retarded, and thus lower the signal-reservoir pressure to a degree dependent upon the strength of the direct impulse. The result was that under a strong impulse the whistle would sound longer and vent more pressure from the signaling-reservoir than under a weaker impulse, and the piston would under all conditions after a direct impulse close the whistle-valve and hold it closed against rebounding impulses to prevent undue repetition of signals. While my aforesaid patented devices operate satisfactorily, they cause under strong signaling impulses a greater venting from the signaling-reservoir, and consequently a greater loss of air, than I find desirable.

My present object is to provide a signal-valve of the non-interference type in which the venting from the signaling-reservoir to the whistle will be nearly the same under direct signaling impulses of different degrees of strength, which will cause a rapid recharging of the signaling-reservoir after each direct impulse, and in the use of which the signals may be repeated more rapidly than in the use of the previous devices.

In the main my present device differs from the previous devices in dispensing with means for retarding the return of the signal-valve piston and in providing means for opening under strong direct impulses the signaling-reservoir through a supplemental passage to the train-pipe. Thus instead of wasting the signaling-reservoir air and prolonging the sound of the whistle the body of air in the signaling-reservoir is thrown into communication with the body of air in the train-pipe to quiet fluctuations instead of permitting them to spend themselves naturally and more slowly. Furthermore, the upper and under sides of the piston will be subjected simultaneously to the force of the fluctuations following a strong direct impulse, which will tend to prevent unseating of the piston under the force of the fluctuations to sound the whistle.

Referring to the drawings, Figure 1 is a ver-

tical section of a signal-valve of my latest improved construction; Fig. 2, a section on the line 2 2 of Fig. 1, corresponding with lines 2 in Figs. 3 and 4; Fig. 3, a broken plan section taken on line 3 of Fig. 2, and Fig. 4 a vertical section of a bushing.

For convenience of construction the signal-valve or valve device A is formed in two sections A' A², fitting and bolted together with a gasket a between them. In the device is a chamber b, provided in its upper part with a bushing b' and communicating at its top through a cored passage b² with the train-pipe at B. In the base of the chamber b, at the center thereof, is an opening b³, communicating with a cored passage c, extending to the signal or whistle C. Mounted in the opening b³ and extending upward in the chamber b is a sleeve or tube d, provided in its lower end with a port d', surrounded by a valve-seat and opening into the whistle-passage c. In the side of the sleeve is a port d², opening into the chamber b. D is the signal-valve piston, sliding in the bushing b' and fitting the same closely. On the upper side of the piston is a chamber e, surmounted by a projection e', and on the under side of the piston is a hollow stem e², fitting and sliding in the sleeve d and terminating above the port d². The chamber e is in open communication with the chamber b above the piston, and in its base surrounding the opening through the stem e' is a valve-seat e³. In the hollow stem e² is a winged stem f, forming at its lower end a valve to close the port d' and provided at its upper end with a valve f', fitting the seat e³. In the chamber e is a spring f², which is confined between the piston and the stem f, tending to hold the latter down to close the port d' and the former up to seat the valve f' on the seat e³. In the lower part of the chamber b is a port g, leading to a passage g', which communicates with the signaling-reservoir at E. Thus far described the construction is similar to that shown in Fig. 1 of my aforesaid Patent No. 620,601.

Above the chamber b and in open communication therewith is a chamber h, fitted with a bushing h'. Above the chamber h is a chamber i, communicating through a passage i' with the train-pipe passage b². Between the chambers i h is a vent-passage i², surrounded at its top in the chamber i by a valve-seat i³ for a check-valve i⁴, which may rise to a stop i⁵. In the bushing h', at one side near its lower end, is a port or pair of ports k, communicating with a cored passage k', extending down the side of the device to the under side of the bushing b' and there communicating with the chamber b. In the chamber h is a piston l, chambered in its under side, as shown at l', and provided at the center of its chamber with a downward-projecting lug l². In the outer surface of the piston l, about midway between its upper and lower ends, is an annular recess l³, communicating through ports with the inner chambered side of the

piston. Above the recess l³ the piston fits loosely the bushing h'; but below the recess l³ the piston fits snugly against the bushing, so as to effectively close the port k when covering the same. At the lower end of the bushing h' is a stop m, which limits the downward movement of the piston l. In the upper side of the piston l is a central socket or recess l⁴, containing a spring l⁵, which is confined between the piston and the upper end of the chamber h.

The operation is as follows: Air under pressure from the train-pipe fills the cored passage b² and passing into the upper part of the chamber b presses down the piston D to unseat the valve f'. The air passes through the direct reservoir feed-passage—namely, the chamber e, stem e², port d², chamber b² at the under side of the piston, port g, and passage g—to fill the signaling-reservoir. The air also passes through the passage i' to the chamber i above the valve i⁴ and through the ports in the piston l to the recess l³, and thence up around the piston l to the upper part of chamber h. When the pressure in the signaling-reservoir and lower part of the chamber b equals approximately that of the train-pipe, the spring f² operates to raise the piston D and close the port e³. The stem or valve f is kept seated over the port d' by the relative suction action at the latter. When what may be termed a "comparatively weak direct signaling impulse" is generated at a conductor's signaling-valve in the train-pipe, the slight lowering of pressure above the piston D causes it to be raised to the stop l², thereby raising the valve f and opening the port d', so that signaling-reservoir pressure escapes from the lower part of the chamber b to the whistle C to sound the same. As soon as the pressure of the signaling-reservoir falls approximately to that of the train-pipe the piston D descends and the valve f closes the whistle-port d'. The subsequent rise of pressure in the train-pipe causes the piston D to be moved downward to open the port e³ and recharge the signaling-reservoir. The fluctuations following such a weak direct impulse will be too mild to disturb the piston D and will quickly subside. Under a strong direct signaling impulse the comparatively great reduction of pressure above the piston D will cause the latter to be raised against the stop l² and press the piston l upward in the chamber h, expelling air from above the piston l through the vent-passage i² and chamber i to the train-pipe. In doing this it unseats the valve i⁴, which quickly seats again when the piston l ceases to rise. The force with which the piston D is lifted will depend upon the strength of the direct impulse, and in the rise of the piston l the port k will be uncovered. The opening of the port k tends to quickly equalize the pressures above and below the piston D, so that the latter will fall and cause the valve f to quickly close the port d' to the whistle. The closing of the check-valve i⁴

renders it necessary for air to pass through the port in the piston *l*, recess *l*³, and around the piston to the upper part of the chamber *h* in order to produce such rise of pressure above the said piston as to permit the same to descend and close the port *k*. The passage of air to the upper part of the chamber *h* in practice will be comparatively slow, because the upper part of the piston is sufficiently close to the bushing to produce that result. In the drawings the space between the upper part of the piston *l* and bushing is greatly exaggerated for the purpose of illustration. While the port *k* is uncovered, which it will be for a time after the whistle-port *d*¹ has been closed, as described, the volume of air in the signaling-reservoir is in open communication with the train-pipe, thereby increasing the volume of air in which the fluctuations following the direct impulse must operate. The tendency of this sudden increase of volume is to absorb to a great extent, at least, the strength of the fluctuations, and at the same time the under side as well as the upper side of the piston *D* will be exposed to the force thereof. Thus as the first rebounding impulse, at least, will act against both sides simultaneously of the piston *D* the latter will not be effected thereby. While the air passes, as described, to the upper part of the chamber *h* the piston *l* will descend to its normal position, closing the port *k*. Theoretically, at least, it is only necessary to absorb the first rebounding impulses which follow upon the direct signaling impulse, because complete destruction of their force would naturally prevent the following thereon of further fluctuations. In the construction shown in the drawings the port or ports *k* are graduated to rapidly increase the size of the opening or supplemental passage between the train-pipe and signaling-reservoir as the piston *l* rises. The resistance of the spring *b*⁵ tends to limit the rise of the piston *l* according to the strength of the signaling impulse, and thus also cause the degree of opening of the supplemental passage to be governed by the strength of such impulse. The spring also tends to hasten the return of the piston *l* to close the supplemental passage. The whole tendency of this construction is to cause quick destruction of the direct and rebounding impulses in the train-pipe instead of permitting them to die out or subside naturally, with the result that the pressure in the train-pipe will be quieted very quickly after each direct signaling impulse, and such impulses may be caused to follow upon each other in rapid succession without danger either of a miss or undue repetition of the signal. A further advantage of this construction lies in the fact that under a sudden rush of pressure to the device from the train-pipe the piston *l* will be lifted, and thus open a large supplemental passage for the pressure to the signaling-reservoir.

While the construction shown and above described is the form in which I now prefer

to embody my improvements in connection with train signaling systems, I do not wish to be limited to the structural details, because they could be variously modified as circumstances may suggest or necessity render expedient without departing from the spirit of my invention as defined by the claims. My invention is also applicable to other fluid-pressure systems besides those in use upon railway-trains and whether a signal to be actuated thereby is audible or visual.

What I claim as new, and desire to secure by Letters Patent, is—

1. In a fluid-pressure signaling system, the combination, with a signal valve device operative by variations of pressure on opposite sides of a movable abutment, of means separate from, but actuated by, the movable abutment, for quickly releasing fluid from one side of the abutment to the other to counteract such variations.

2. In a fluid-pressure signaling system, the combination, in a signal valve device, of a movable abutment exposed on one side to pressure in a signaling-pipe and on the other to pressure in a reservoir, a valve device operated by the movable abutment to supply fluid under pressure to a whistle or other alarm device, and means separate from, but actuated by, the movable abutment, for quickly releasing fluid under pressure from the reservoir to the train-pipe side of the abutment so as to reduce the reservoir-pressure and to counteract reductions of pressure in the train-pipe.

3. In a fluid-pressure signaling system, the combination, in a signal valve device, of a movable abutment exposed on one side to pressure in a signaling-pipe and on the other side to pressure in a reservoir, a valve device operative by the abutment, on a reduction of pressure in the signaling-pipe, to release fluid under pressure from the reservoir to a whistle or other alarm, and means separate from, but actuated by, the movable abutment, whereby the reservoir may be connected with the signaling-pipe so that both sides of the abutment will be exposed to the same variations of pressure in the signaling-pipe after the first reduction of pressure therein.

4. In a fluid-pressure signaling system, the combination, in a signal valve device, of a movable abutment exposed on one side to pressure in a signaling-pipe and on the other side to pressure in a reservoir, a valve device operated by the movable abutment to release fluid under pressure from the reservoir to a whistle or other alarm device, and means separate from, but actuated by, the movable abutment, for suddenly equalizing the pressures on both sides of the movable abutment.

5. In a fluid-pressure signaling system, the combination, in a signal valve device, of a movable abutment exposed on one side to pressure in a signaling-pipe and on the other side to pressure in a reservoir, valve mechanism operated by the movable abutment to re-

lease fluid under pressure from the reservoir to a whistle or other alarm device and means separate from, but actuated by, the movable abutment, for releasing fluid from the reservoir to the signaling-pipe.

6. In a fluid-pressure signaling system, the combination with a signal valve device provided with valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed passage extending between the signaling-pipe and signaling-reservoir, and valve mechanism, governing said passage actuated, under strong signaling impulses in the signaling-pipe, to open said passage, to subject rebounding impulses following the direct signaling impulse to the modifying effect of the volume of signaling-reservoir air, and then close said passage, substantially as and for the purpose set forth.

7. In a fluid-pressure signaling system, the combination with a signal valve device provided with piston-actuated valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed passage extending between the signaling-pipe and signaling-reservoir, and valve mechanism, governing said passage, actuated, under strong signaling impulses in the signaling-pipe, to open said passage, to subject both sides of the piston of the piston-actuated valve mechanism simultaneously to the force of rebounding impulses following the direct signaling impulse, and then close said passage, substantially as and for the purpose set forth.

8. In a fluid-pressure signaling system, the combination with a signal valve device provided with valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed supplemental passage extending between the signaling-pipe and signaling-reservoir, and quickly opening and slowly closing valve mechanism governing said passage, actuated under signaling impulses in the signaling-pipe to open and then close said passage, substantially as and for the purpose set forth.

9. In a fluid-pressure signaling system, the

combination with a signal valve device provided with piston-actuated valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed supplemental passage extending between the signaling-pipe and signaling-reservoir, and valve mechanism governing said passage, in the path of the said piston-actuated valve mechanism, and actuated by movement of the said piston-actuated valve mechanism to open and then close said passage, substantially as and for the purpose set forth. 85

10. In a fluid-pressure signaling system, the combination with a signal valve device provided with piston-actuated valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed supplemental passage extending between the signaling-pipe and signaling-reservoir, self-closing supplemental-passage valve mechanism, in the path of the said piston-actuated valve mechanism, actuated by movement of the said piston-actuated valve mechanism to open said passage, and return retarding means for the supplemental-passage valve mechanism for yieldingly resisting the closing movement thereof, substantially as and for the purpose set forth.

11. In a fluid-pressure signaling system, the combination with a signal valve device provided with piston-actuated valve mechanism interposed between a signaling-pipe and a signaling-reservoir, and subject on its opposite sides to pressure therefrom, respectively, and normally closing an outlet to the signal, and movable from normal position to open said outlet under pressure from the said reservoir when the signaling-pipe pressure falls under a signaling impulse, of a normally closed supplemental passage extending between the signaling-pipe and signaling-reservoir, supplemental-passage valve mechanism, in the path of the said piston-actuated valve mechanism, actuated by movement of the said piston-actuated valve mechanism to open said passage, a spring operating to resist the opening and assist the closing of the supplemental-passage valve mechanism, and return retarding means for the supplemental-passage valve mechanism for yieldingly resisting the closing movement thereof, substantially as and for the purpose set forth. 115

12. In a fluid-pressure signaling system, the combination, with a signal valve device, operative by variations of pressure on opposite

sides of a movable abutment, of means for establishing communication between the opposite sides of the abutment when it is operated to make a signal, and for independently closing such communication.

13. In a fluid-pressure signaling system, the combination, with a signaling-pipe and a signal valve device, operative by variations of pressure on opposite sides of a movable abutment, of a signaling-reservoir, means actuated by the movable abutment for establish-

ing communication between the reservoir and the signaling-pipe, and for independently closing the communication after a return movement of the abutment. 15

In testimony whereof I have hereunto set my hand.
